(57) **CLAIM**

The ornamental design for a towel dispenser, as shown and described.

DESCRIPTION

FIG. 1 is an isometric view of a towel dispenser according to our new design;

FIG. 2 is a front side elevation view of the towel dispenser of FIG. 1;

FIG. 3 is a rear side elevation view of the towel dispenser of FIG. 1;

FIG. 4 is a left side elevation view of the towel dispenser of FIG. 1;

FIG. 5 is a right side elevation view of the towel dispenser of FIG. 1;

FIG. 6 is a top plan view of the towel dispenser of FIG. 1; and,

FIG. 7 is a bottom plan view of the towel dispenser of FIG. 1.

The dot-dash broken lines shown in the drawings are boundary lines and the uniform broken lines illustrate environment only and each form no part of the claimed design.
